C. E. Hitchings

By Victor J. Evans
Attorney

UNITED STATES PATENT OFFICE.

CHARLES E. HITCHINGS, OF BRADENTOWN, FLORIDA.

PROPELLING MECHANISM.

Application filed April 27, 1925. Serial No. 26,244.

To all whom it may concern:

Be it known that I, CHARLES E. HITCHINGS, a citizen of the United States, residing at Bradenton, in the county of Manatee 5 and State of Florida, have invented new and useful Improvements in Propelling Mechanisms, of which the following is a specification.

This invention contemplates the provision 10 of a propelling mechanism for boats, including propeller blades arranged in pairs at each side of the boat and always maintained perpendicular, the blades of one pair at each side being down when the other 15 adjacent pair is up, thus providing for a well balanced arrangement and an almost continuous pull while the mechanism is in operation.

The nature and advantages of the invention 20 will be better understood when the following detailed description is read in connection with the accompanying drawings, the invention residing in the construction, combination and arrangement of parts as 25 claimed.

In the drawings forming part of this application, like numerals of reference indicate similar parts in the several views, and wherein:

30 Figure 1 is a plan view showing the invention associated with a boat.

Figure 2 is a side elevation of the boat showing the mechanism mounted thereon.

35 Figure 3 is a sectional view taken on line 3—3 of Figure 2.

Figure 4 is a view of one pair of propeller blades.

40 Figure 5 is a fragmentary view of one of the crank shafts.

Referring to the drawings in detail, A indicates generally a boat of any well known construction in which is arranged a motor B of any suitable type.

45 Arranged transversely of the board and journaled in suitable bearings thereon is a pair of spaced parallel shafts 10 and 11 respectively which rotate in unison, the shafts being connected by an endless chain 12 which is trained over suitable sprockets

50 mounted on said shafts as clearly shown in Figure 1. The shaft 10 is driven from the motor B, and for which purpose the motor shaft is provided with a small bevelled gear 13 which meshes with a similar gear 14 fixed upon the shaft 10. Motion 55 from this shaft is then transmitted to the

shaft 11, by means of the endless chain above referred to. Each shaft projects beyond the sides of the boat, and each end supports crank arms 15 and 16 respectively, the latter being comparatively long as illustrated in Figure 5. The crank portion for the arm 15 is indicated at 17, while the crank portion for the arm 16 is indicated at 18. By reason of this construction, it is 60 possible to mount two pairs of propeller blades at each side of the boat, the crank portions of the respective arms at each side of both being utilized for this purpose. In other words, the paddle blades indicated at 19 are used in pairs, and each pair is connected by a rod or the like 20 which supports bearings 21 as clearly shown in Figure 4. The bearings 21 of one pair of propeller blades receive the corresponding 70 crank portions 17 of the adjacent arms 15 at each side of the boat, while the other pair of propeller blades are similarly associated with the crank portions 18, it will 75 be manifested that the propeller blades are 80 always mounted perpendicularly and when the shafts 10 and 11 are rotating the propeller blades are operated with a step by step motion. In other words, one pair of blades at each side of the boat moves down in 85 the water while the other pair at the same side of the boat are being moved upwardly, the construction providing for a well balanced arrangement, and at the same time providing for a more or less continuous pull 90 through the water. Consequently, the boat 95 can be operated with a minimum consumption of fuel with the development of reasonably high speed.

While it is believed that from the foregoing description, the nature and advantages of the invention will be readily apparent, I desire to have it understood that I do not limit myself to what is herein shown and described, and that such changes 100 may be resorted to when desired as fall within the scope of what is claimed.

Having thus described the invention, I claim:

1. A propeller mechanism for boats comprising spaced parallel shafts arranged transversely of the boat, means for rotating said shafts simultaneously, spaced pairs of propeller blades supported by the adjacent ends of said shafts at each side of the 105 boat, and always maintained perpendicularly, said blades in pairs alternately moving 110

in and out of the water to provide for a continuous pull.

2. A propeller mechanism for boats comprising spaced parallel shafts journalled 5 transversely of the boat, means for rotating said shafts simultaneously, spaced parallel arms supported by each end of each shaft, a crank portion forming part of each arm, with the crank portions of the adja- 10 cent arms arranged in different horizontal

planes, spaced pairs of propeller blades arranged at each side of the boat, a rod connecting the blades of each pair, the ball of each pair being journalled on the crank portions of the respective arms, whereby said 15 blades in pairs alternately move in and out of the water to provide for a continuous pull.

In testimony whereof I affix my signature.
CHARLES E. HITCHINGS.
